UNITED STATES PATENT OFFICE

JAMES AUGUSTINE MELLON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

ELECTRIC STEERING DEVICE

Application filed September 5, 1928. Serial No. 304,017.

This invention relates to improvements in electric steering devices, and the principal object of the invention is to provide a machine of this character which shall be exceptionally compact in form, efficient and substantially noiseless in operation, and which shall have certain structural advantages hereinafter set forth.

Another object of the invention is to provide a machine of the stated type in which substantially all of the working parts shall be completely enclosed within a housing of suitable form.

In the attached drawings:

Fig. 1 is a longitudinal vertical section through a machine made in accordance with my invention;

Fig. 2 is a section on the line 2—2, Fig. 1;

Fig. 3 is an end elevation of the drum end 20 of the machine with the drum and end plate removed;

Fig. 4 is a more or less diagrammatic side elevational view illustrating a typical assembly, and

Fig. 5 is a diagrammatic plan view of the machine and associated steering apparatus.

With reference to the drawings, the machine comprises a substantially barrel-shaped main housing 1 having a pedestal 2. Secured to one end of the housing 1 is a sub-housing 3 which constitutes in effect an extension of the main housing and closes that end of the main housing to which it is secured. The interior of the main housing 1 is separated from the interior of the sub-housing 3 by the interior end wall 4 of the latter. Secured in and closing the other end of the housing 1 is an end member 5, this member being secured to an annular flange 6 on the said housing located inwardly of the extremity of the housing. The end member 5 projects outwardly and has a gudgeon 7 which constitutes a fixed bearing for a rotary grooved drum 8, this drum comprising at its base a flange 9 which projects into the end of the housing and which carries an internal gear 10 by means of which the drum is operated, as hereinafter set forth. The drum is secured on the gudgeon 7 by means in the present instance of a plate 11, which is secured to the

extremity of the gudgeon and overlaps the outer end of the hub portion of the drum.

The casing also comprises an interior partition 12 to which is secured by means of bolts 13 an end mounted electric motor 14, 55 said motor also being supported at its rear end upon a bracket 15 extending upwardly from the floor of the housing. The armature shaft 16 of the motor projects through the partition 12 and carries a pinion 17 which 60 through a train of spur gearing including a gear and pinion 18—19, journaled on a stud 20 in the partition 12, and a gear and pinion 21—22 on a stud 23 in the end member 5, is connected with a gear 24 on a shaft 25, 65 this shaft being journaled in bearings 26, 27 and 28 located respectively in the partition 12, the flange 6, and the inner wall 4 of the sub-housing 3. At one end of this shaft 25 is a pinion 29 which meshes with the internal gear 10 and completes the operative connection between the drum 8 and the motor 14. The motor 14 is provided with a suitable brake 30.

It will be noted that the lower part of the 75 gear 24 operates in a well 31 between the partition 12 and the flange 6 which is adapted to contain oil and which affords a means for lubricating the spur gear transmission between the motor and the drum. The bearing 80 27 of the shaft 25 is also provided at the top with a cup 32, from which lubricant passes to the shaft journal.

The sub-housing 3 encloses the motor control and follow-up mechanism. This mechanism comprises a shaft 33 journaled at one end in the outer wall 34 of the sub-housing 3, and at the opposite end in a bevel pinion 35, this pinion being journaled in the inner wall 4 of the sub-housing. Keyed to the 85 shaft is a second and oppositely arranged bevel pinion 36 which with the bevel pinion 35 and with a third pinion 37, which meshes with both the pinions 35 and 36 and which is journaled on a yoke 38 pivotally mounted 90 on the shaft 33, constitutes a differential device whose function will be hereinafter described. The yoke 38 carries contact elements 39 which with a series of relatively fixed contacts 40 constitute a set of switches 100

controlling the operation of the motor 14. At its outer end, the shaft 33 carries a gear 41 which through intervening gears 42 is connected with a pinion 43 upon a stub shaft 44 journaled in the outer wall of the sub-casing 3, and this shaft as illustrated in Figs. 4 and 5 is adapted to carry on its outer end a grooved drum 45. The pinion 43 is also connected with a pinion 46 on a screw shaft 47 journaled at 48, 48 in the bottom of the sub-housing, and this shaft carries a rider nut 49 which, when the shaft 47 is rotated, is moved in one direction or the other, depending upon the direction of rotation. The movement of the rider 49 is limited by set screws 50, 50 in the bottom of the sub-housing. The elements 47, 49 and 50 constitute stops limiting the rotation of the stub shaft 44 in both directions.

20 The bevel pinion 35 carries at the inner end and within the main housing 1 a gear 51 which through an intervening train of gears 52 is connected with a pinion 53 upon the end of the shaft 25 whereby the said bevel pinion 35 is operatively connected with the motor 14. It will be noted that the motor control mechanism is detachable as a unit with the sub-housing.

30 As shown in Figs. 4 and 5, the steering machine as described above is adapted to be operatively connected with a steering wheel 54, this connection being made in the present instance through the drum 45, a cable 55 connected with said drum and also with a grooved drum 56 at the bottom of the steering shaft with which the wheel 54 is connected. Any movement of the wheel 54 is thus transmitted to the drum 45. The drum 8 of the machine is adapted to be connected as shown in Fig. 5 through a suitable cable 57 with a sector 58 on the rudder post 59. In operation, movement of the wheel 54 results through the intermediate elements including the drum 45 and intervening train of spur gears in a rotative movement of the shaft 33, and through the differential mechanism results in oscillation of the yoke 38 and contact elements 40. This movement of the yoke through the differential is made possible by 40 the fact that the bevel pinion 35 forming a part of the differential is temporarily fixed, the motor 14 being inoperative. The movement of the switch elements 39 in relation to the contact elements 40 results in an actuation of the motor 14 which actuates the steering drum 8 in an amount proportionate to the movement of the wheel 54, and this actuation of the motor 14 also results through 50 the shaft 25 and intervening train of gears 60 in a rotative movement of the bevel pinion 35, which results in a return of the movable switch elements 39 to their original or neutral position. The direction of movement of the steering wheel 54 determines the direction of rotation of the motor 14, and the

limit screws 50 are adjusted to prevent an overtravel of the wheel 54 in either direction.

It will be apparent that the aforescribed construction affords an extremely compact machine in which the motor and major portion of the transmission and control mechanisms are completely enclosed. The machine is highly efficient in operation, and by reason of the complete enclosure of the operating elements is practically noiseless.

75 I claim:

1. An electric steering machine comprising a substantially barrel-shaped main housing, a sub-housing constituting a closure for one end of the main housing, an end member closing the other end of the main housing, a grooved drum journaled for rotation on said end member, an electric motor mounted in said main housing and operatively connected with said grooved drum, and motor control mechanism mounted in said sub-housing and also operatively connected with the drum.

80 2. In a steering machine, the combination with a main housing, a sub-housing secured to one end of the main housing, a rotary drum mounted at the other end of the main housing, a motor mounted in said main housing and operatively connected with the drum, motor control mechanism mounted in said sub-housing and removable from said main housing with the sub-housing as a unit, and means operatively connecting the said control mechanism with the drum.

85 3. A steering machine comprising a substantially barrel-shaped main housing, a sub-housing constituting a closure for one end of the main housing, an end member secured in and closing the other end of the main housing, a rotary drum mounted at the last-named end of the main housing, a motor mounted and completely enclosed within the main housing and operatively connected with the drum, and motor control devices mounted in the sub-housing and also operatively connected with the drum.

90 100 4. A steering machine comprising a substantially cylindrical open-ended housing member, a sub-housing constituting a closure for one end of said housing member, an end member secured in and closing the other end of said housing member, a drum journaled on said end member, a motor mounted and completely enclosed within said housing, transmission spur gearing connecting the motor with the said drum, and motor control mechanism mounted in said sub-housing and comprising elements mechanically connected with said drum.

105 110 115 120 125 5. In a steering machine, the combination with an open-ended main housing member having a partition, a motor secured to said partition, an end member secured in and closing one end of the main housing member, a rotary drum mounted at the same end of said housing, transmission mechanism sup-

ported on said partition and on said housing end member and connecting the said drum with the motor, a sub-housing constituting a closure for the other end of said main housing member, and motor control mechanism mounted in said sub-housing and operatively connected with the motor.

6. In a steering machine, the combination with an open-ended substantially barrel-shaped main housing member, of a sub-housing constituting a closure for one end of said member, an end plate secured in and closing the other end of said member, a rotary drum journaled on said end plate and comprising an inwardly projecting flange, an internal gear secured in said flange, a shaft journaled in said housing, a motor mounted in the housing, transmission mechanism operatively connecting the motor with said shaft, motor control mechanism mounted in said sub-housing and operatively connected with said shaft and with the motor, and a pinion on said shaft meshing with said internal gear.

25 7. A steering machine comprising a substantially barrel-shaped main housing member; an end plate secured in and closing one end of said housing member, a portion of said main housing overhanging said end member; a drum journaled on said end member and having a flange extending into the overhanging end of said housing member; an internal gear secured to the inner face of said flange; a shaft journaled in the housing and having one end projecting through said end member; a pinion on the projecting end of said shaft meshing with said internal gear; a motor mounted in said housing; gearing connecting the motor with said shaft; a sub-housing secured in and closing the opposite end of the housing member from said drum; and gearing operatively connecting said control mechanism with said shaft.

45 8. In a steering machine, the combination with an open-ended housing member; of a sub-housing secured to and closing one end of said housing member; an end plate secured in and closing the other end of said housing member; a drum mounted at the latter end of the housing; a motor mounted within the housing; a shaft journaled in the housing and geared to said drum; gearing connecting the shaft with the motor; motor control mechanism in said sub-housing, said control mechanism including switches for controlling the operation of said motor, switch-actuating mechanism, and manual control means for said mechanism; and means operatively connecting said mechanism with the said shaft.

60 9. In a steering machine, the combination with an open-ended housing member of a sub-housing secured to and closing one end of said housing member; an end plate secured

in and closing the other end of said housing member; a drum mounted on the latter end of the housing; a motor mounted within the housing; a shaft journaled in the housing and geared to said drum; gearing connecting the shaft with the motor; motor control mechanism in said sub-housing, said control mechanism including switches for controlling the operation of said motor, switch-actuating mechanism, and manual control means for said mechanism; means operatively connecting said mechanism with the said shaft; and adjustable means for limiting the movement of said manual actuating means.
